UNITED STATES PATENT OFFICE.

WILLIAM HAWKS, OF CHICAGO, ILLINOIS, ASSIGNOR TO CHICAGO SOLAR LIGHT COMPANY, OF CHICAGO, ILLINOIS, A CORPORATION OF ILLINOIS.

HYDROCARBON-LAMP.

SPECIFICATION forming part of Letters Patent No. 705,582, dated July 29, 1902.

Application filed October 17, 1900. Serial No. 33,379. (No model.)

To all whom it may concern:

Be it known that I, WILLIAM HAWKS, a citizen of the United States, residing at Chicago, in the county of Cook and State of Illinois, 5 have invented certain new and useful Improvements in Hydrocarbon-Lamps, of which the following is a specification.

The object of this invention is the production of an air-pressure hydrocarbon-lamp embodying the improvements hereinafter described.

In the accompanying drawings, Figure 1 is a vertical central section through my improved hydrocarbon-lamp. Fig. 2 is a central section through the air-valve by means of which air is introduced into the lamp-body. Fig. 3 is a view showing the screen in the upper end of the burner-tube.

Like letters of reference indicate corresponding parts throughout the several views.

In the construction of this lamp I provide the body portion A, in this instance substantially of globular form, having the base A', upon which the lamp is supported. The globular body portion A is hollow, the interior being a receptacle for containing hydrocarbon and air under pressure. An air-valve B provides means for filling the lamp, also for placing the hydrocarbon under air-pressure, the tube B', to which an air-pump may be connected, communicating with the interior of the lamp-body.

C is a hydrocarbon feed-pipe extending vertically through the lamp-body to a point near the bottom thereof. This feed-pipe is continued at its upper end in the tube C', which conducts hydrocarbon upward to the needle-valve, to be later described.

D is the needle-valve casing, formed integral with said hydrocarbon-pipe C at the upper end thereof. The rear end of said casing is internally screw-threaded at D' to receive the needle-valve stem and externally screw-threaded for the stuffing-box D². The 45 casing D extends forward in the generating-sleeve D³ across the heated zone above the lamp-burner, to be mentioned later herein, and is fitted at its outer end with the screw-threaded centrally-perforated discharge-tip D⁴, adapted to receive the conical closure of the needle-valve and the needle-point there-

of. A generating-cup D⁵, containing a quantity of mineral wool, has a loop D⁶ for surrounding the sleeve D³, whereby the cup is supported beneath said sleeve and may be slid along the same to apply heat to it at any desired point in starting the lamp. E is a mixing-tube extending downward from the discharge-tip D⁴ of said needle-valve casing D to a point near the body portion A of the lamp, turning thence upward, and at this upturned end is fitted with the removable burner-tube E'. This burner-tube has the usual screw-clip E² for the mantle-supporting arm E³. In the upper end of the burner-tube E', I have placed a screen F, composed of a spiral coil or roll of two sheet-metal strips F' and F², the former being flat and the latter crimped. I have obtained results very favorable in the use of this form of screen, 70 not only in its greater durability over the wire screen formerly used, but in an increased steadiness in the light produced.

The upper horizontal portion of the mixing-tube E is screw-threaded to receive the mixing-bell G, the collar G' of which bell is internally screw-threaded to correspond with the screw-threads just mentioned on the mixing-tube E. The bell G is hollow and is closed except for the perforations G² in its forward (inner) face near the periphery of the bell G and the opening in its center for the admission of the discharge-tip D⁴ of the needle-valve casing D. The screw-thread mounting of the mixing-bell G upon the mixing-tube permits of a movement of said bell toward or from the end of the discharge-tube to vary the quantity of air which is mixed with the hydrocarbon gas during the operation of the lamp.

A needle-valve stem H is adapted to be inserted within the needle-valve casing D and the generating-sleeve D³. Its enlarged rear portion H' is screw-threaded to correspond with the internal screw-threads of the needle-valve casing D, whereby it is moved forward and back to open and close the needle-valve. Forward of the enlarged screw-threaded portion H' the needle-valve stem is screw-threaded for the greater portion of its length. This 100 last-mentioned screw-threaded portion H² is of a diameter but slightly less than the inter-

nal diameter of the sleeve D³, so that the needle-valve stem H will fit the sleeve D³ rather snugly, leaving the thread depressions on the valve-stem H as the only space for the passage of the hydrocarbon and gas. This space is so slight that the generation of gas from the liquid is rendered almost instantaneous. At its extreme forward end the needle-valve stem H is provided with the conical closing-face H³, adapted to enter the central perforation of the discharge-tip D⁴ and with the needle-point H⁴ for cleaning the small discharge-opening of said tip. The needle-point H⁴ is formed by drilling into the forward end of the needle-valve stem H and inserting into the hole thus formed a piece of wire, securing the latter in its position by solder or other suitable means. At its rear end the needle-valve stem is provided with the usual hand-button H⁵.

In operation hydrocarbon is introduced into the lamp-body through the air-valve B. After a sufficient quantity of the liquid has been poured into the receptacle an air-pump is connected with the tube B' of the air-valve and the liquid in the receptacle placed under air-pressure. The pressure of the air in the upper portion of the receptacle A drives a column of the hydrocarbon upward in the pipe C adjacent to the needle-valve, filling the screw-thread spaces in the needle-valve stem within the sleeve D³. A quantity of alcohol is placed within the generating-cup D⁵, said

cup slid along the sleeve D³ to the desired point, and the alcohol ignited. When the hydrocarbon within the sleeve is heated to such a degree that it assumes the form of a gas, the needle-valve is opened and the gas in the casing discharged under the existing pressure through the needle-valve opening into the mixing-bell G. The force of the incoming jet is sufficient to carry said gas downward in the mixing-tube E and upward to the burner-tube through the screen F in said tube and in the mantle where it is consumed. 45

I claim as my invention—

In a hydrocarbon-lamp, in combination, a needle-valve casing having a generating-sleeve; a needle-valve stem fitting said sleeve snugly and being screw-threaded to form a channel for the passage of the hydrocarbon and gas within said sleeve, said stem being provided with a wire point of uniform diameter; a mixing-tube; and a mixing-bell provided with a perforated forward face having a central opening to receive the end of the needle-valve casing, the rear face of said bell being provided with a collar having a screw-thread connection with mixing-tube, to provide for an adjustment of said bell to and from the valve-casing. 55 60
